UNITED STATES PATENT OFFICE

147,168

DESIGN FOR A PAIR OF SUNGLASSES

Luis Alvarez Villanueva, Madrid, Spain

Application August 30, 1946, Serial No. 132,985

Term of patent 3½ years

(Cl. D57—1)

To all whom it may concern:

Be it known that I, Luis Alvarez Villanueva, a citizen of Spain, of Puerta del Sol 5-1D, Madrid, Spain, have invented a new, original, and ornamental Design for a Pair of Sunglasses, of which the following is a specification, reference being had to the accompanying drawings, forming part thereof.

Figure 1 is a plan view,

Fig. 2 is a front view, and

Fig. 3 is a side view of a pair of sunglasses, showing my new design.

I claim:

The ornamental design for a pair of sunglasses, as shown.

LUIS ALVAREZ VILLANUEVA.
